United States Patent Office

Des. 218,328
Patented Aug. 11, 1970

218,328

CABINET

Wilbur Rone, 178 Rockhill Road,
Asheville, N.C. 28803

Filed Apr. 18, 1969, Ser. No. 16,810

Term of patent 3½ years

Int. Cl. D6—01

U.S. Cl. D33—19

FIG. 1

FIG. 2

FIG. 1 is a perspective view of my new and original cabinet in a closed position; and

FIG. 2 is a perspective view of my cabinet in a fully opened position.

The side of the cabinet not shown is similar in appearance to the side shown, while the back of the cabinet is plain and unornamented.

I claim:

The ornamental design for a cabinet, as shown and described.
